UNITED STATES PATENT OFFICE.

MORRIS J. HOFFMAN, OF CHICAGO, ILLINOIS.

MACHINE FOR REWINDING WOVEN FABRICS.

1,240,800.

Specification of Letters Patent. Patented Sept. 18, 1917.

Application filed January 6, 1917. Serial No. 140,886.

To all whom it may concern:

Be it known that I, MORRIS J. HOFFMAN, a citizen of the United States, and a resident of Chicago, county of Cook, and State 5 of Illinois, have invented certain new and useful Improvements in Machines for Rewinding Woven Fabrics, of which the following is declared to be a full, clear, and exact description.

10 This invention relates to machines for rewinding woven fabric and it has been designed particularly for use in doubling and rewinding linings into bolts. In cutting linings, it has been the custom to cut each 15 part of the garment lining in duplicate, and in order to accomplish this in a fairly economical manner, it has been customary heretofore to unwind the bolt of lining, double the lining upon itself, and rewind it upon 20 the board upon which it was previously wound. This operation of doubling and rewinding has heretofore been done by hand, and the present machine has been designed to accomplish this task by means of mechanism 25 whereby the work may be lightened and whereby the time required for doubling and rewinding the lining is reduced very materially. The invention, therefore, consists in a machine having means whereby 30 one-half of the lining may be unwound from the bolt, and thereafter the lining doubled upon itself at the middle, and the two halves rewound upon a board. The invention further consists in the several novel features of 35 construction, arrangement and combination of parts hereinafter fully described, and particularly defined in the appended claims.

The invention is clearly illustrated in the drawings, accompanying the specifications, 40 in which Figure 1, is an end elevation of a machine embodying a simple form of the present invention; Fig. 2, is a front elevation, looking in the direction of the arrow 2, in Fig. 1; Fig. 3, is a detail vertical cross section taken on the line 3—3 of Fig. 2; Fig. 4, is a detail end elevation of certain gearing, looking in the direction of the arrow 4, in Fig. 2; Fig. 5, is a perspective view of a certain board carrying head; Fig. 50 6, is a detail longitudinal section taken on the line 6—6 of Fig. 2; Fig. 7, is a plan, partly broken away, of a certain gage and associated mechanism; Fig. 8, is a front elevation of the parts seen in Fig. 7; Fig. 9, 55 is a detail cross section taken on the line 9—9 of Fig. 7; Fig. 10, is a perspective view

of a certain bolt supporting head, and Fig. 11, is a perspective view of a rod securing plate used in connection with said head.

Referring to said drawings, which illustrate a simple embodiment of the present invention, 12, 12, designate the end frame members, which may be of any suitable substantial construction, and said end frame members are spaced apart to receive certain 60 members of the winding and rewinding devices. Journalized upon stud shafts 13, secured to the end members, are two bolt supporting heads, 14, which are adapted to support a bolt of cloth or lining during the 65 unwinding and rewinding process. Each of said heads 14, has sockets 15, one at each end, for receiving the ends of rods 16. Means are provided whereby the rods may be readily inserted into said sockets, and whereby they 70 may be positively held therein, and said means is here shown to comprise a plate 16¹, one for each head, and having portions 16^a, extending over the sockets 15. Said plate is 75 adapted to be moved lengthwise to uncover 80 said sockets, whereby the rods may be removed therefrom or inserted thereinto, and it is here shown as formed with a slot 17, extending lengthwise of the plate through 85 which a screw 17^a, passes, and is threaded in the hub 18, of the head; when clamped down 90 upon the plate, it secures it in place. By loosening the said screw, 17^a, the plate may be moved lengthwise to uncover the sockets.

Above the heads 14, are rewinding heads 90 19, which are rotatively mounted upon short shafts 20, 21, carried by the end frame members 12; the shaft 20, is movable lengthwise 95 in its support, and is spring pressed toward the heads 14, by a spring 22, (see Fig. 6) one end of which abuts against an end wall of a socket in which the spring is confined, the other end of which abuts against a collar secured upon the shaft 20. The heads, 19, are 100 formed with hubs 23, secured to said shafts 20, 21, and also formed with elongated socket members 24, having long narrow sockets for receiving the ends of the boards, 25, such as are employed in bolts of material. The hubs, 23 of the heads 19, are also provided 105 with non-circular, axially disposed sockets, 26, that are adapted to receive the non-circular ends of a rod 27. In the arrangement shown, the elongated socket members 24, are placed close to the axis of rotation of the 110 heads so as to leave a slight space between the board 25, and the rod 27.

Above the rewinding heads is a drum 28, which is here shown in the form of four blades, or vanes, projecting radially from a central hub, although this construction is immaterial to the invention, broadly considered. Said drum is mounted upon a shaft 29, journaled in bearings in the end frame members 12, and at one end of the machine, said drum shaft 29, and the shaft 21, project beyond the end frame member and carry pinions 30, 31, on their ends. Mechanism is provided for alternatively rotating the rewinding heads, 19, and the drum, 28, and said means is shown in the drawings to comprise a gear wheel 32, mounted upon a stud shaft 33, carried by a lever 34, which is pivotally supported between the pinions 30, 31, by a bolt or shaft 35, secured in the end frame member. Said lever 34, has a handle 36, by means of which it may be manipulated, and it is also provided with a pin 37, which is adapted to enter either of the two notches 38, 39, formed in a segmental part 40, of the end frame member, which segment is concentric with respect to the bolt, 35. This arrangement permits the driving wheel 32, to be meshed with the pinion, 30, or the pinion 31, whereby the operator may drive either pinion and therewith rotate the rewinding heads 19, or the drum 28. A handle 41, is provided on the driving wheel 32, whereby it may be turned by hand.

Mechanism is provided for indicating to the operator when one-half of the cloth or lining has been unwound from the bolt, or rather when the middle of the lining has reached a point, which, if moved back to the place occupied by the rod 27, will bring the middle portion of the lining into coincidence with said rod. A simple form of indicating mechanism will now be described.

Extending between the end frame members 12, and mounted thereon, is a rod, 42, around which is a tube or long roller 43, over which the woven fabric is moved in winding the same upon the drum 28, or in rewinding it on the rewinding device. Secured upon said roller 43, with screws or otherwise, are two collars 44, that may be adjusted along the roller 43, in accordance with the width of the fabric, and said collars act as guides between which the woven fabric travels. Pivotally supported upon the end frame members, is a supporting member, 45, (see Figs. 7 and 8) which is here shown as comprising a long bar 46, which extends between the end frame members, the bar being bent near its ends to provide two short arms 47, that are pivotally mounted upon the end frame members. Journaled upon the arms 47, of said supporting member 45, is a shaft 48, upon which are mounted two friction rollers 49, that rest upon the roller 43, or upon the fabric which travels thereon. In the operation of

the machine, when the fabric is pulled past said rollers 49, it causes rotation of said rollers and therewith rotation of the shaft 48. Said shaft is provided with a screw threaded portion 50, upon which screw threaded portion is a nut 51 (see Fig. 9). To said nut, 51, is secured a pointer body 52, which has lugs 53, 54, overhanging the bar 46, of the carrying member 45. Said bar 46, is provided with a graduated scale 55, and the lug 54, acts as a pointer. Adjustably secured along the bar 46, is an indicator 56, which has a set screw 57, adapted to bear against the bar for securing said indicator in place thereon. This indicator may be adjusted along the graduated scale, and set at the place where, when the pointer 54, has been moved to a point coincident with the edge 58, of the indicator, the middle of the fabric has been brought into such a position that if moved into a line coincident with the rod 27, one-half of the fabric will have been unwound from the bolt and wound to said rod. A table 61, is secured to the end frame members, and is convenient for laying the bolt thereon.

In the operation of the machine, the operator takes a bolt of lining or other woven fabric, which in accordance with the common and well known practice has been wound around a thin board *a*, and thrusts the rods 16, through the center of the bolt, alongside of the board *a*, uncovers the sockets 15, in the heads 14, places the ends of the rods in said sockets, shifts the plates 16 to cover the sockets and thereafter turns down the screws to hold the plates 16, in place. He then brings the fabric, which is illustrated at A, in Fig. 3, over the roller 43 (the carrying member 45, having been raised therefrom) and secures the end of the fabric upon the drum 28. When the drum is in the form shown in the drawing, one or more spring clips 60, are clamped over the cloth and over one of the vanes of the drum 28, to secure the end of the fabric thereto. The carrier 45, is then lowered to bring the rollers 49, to rest upon the roller 43, or rather upon the fabric on the roller. The operator having first learned the length of the cloth of the bolt sets indicator 56, at the proper place on the scale 55, which indicates the point where the pointer 54, will arrive when one-half of the fabric has been unwound. The lever 34, is then raised to bring the driving gear 32, into mesh with the pinion 30, and the pin 37, moved into the notch 38, of the segment. The driving gear wheel 32, is then rotated in the direction of the arrow thereon in Fig. 4, and the drum 28, consequently rotated in the direction of the arrow thereon, in Fig. 3. As the fabric passes the rollers 49, the latter are turned by reason of the friction between the fabric and rollers, and the screw threaded shaft 48, is there-

upon rotated in the direction of the arrow in Fig. 3. Rotation of the shaft 48, causes the nut 51, and pointer 52, to travel along the shaft 48, and bar 46, and when the pointer coincides with the edge 58, of the indicator 56, the operator stops turning the driving wheel because one-half of the fabric has been unwound, and the middle thereof is in a position, which, when moved toward the rod 27, will coincide with it. The operator then takes the rod 27, and places it in front of the fabric A, pushes the fabric back toward the board 25, which is held in the sockets of the socket members 24, of the heads 19, and inserts the rod 27, into the sockets 26, of the heads 19, thereby holding the fabric between the rod 27 and the board 25. Thereafter, he lowers the lever 34 to its lowermost position, thereby bringing the driving gear wheel 32, into mesh with the pinion 31. Thereupon, he turns the driving wheel in the same direction in which he turned it while unwinding one-half of the fabric, thereby causing the board 25, to rotate in the direction indicated by the arrow in Fig. 3, and thereby winding upon said board the ends of the fabric carried by the heads 14, and by the drum 28. The operator continues to turn the wheel until all of the fabric has been unwound from said parts and rewound upon the board 25. It will be understood that in rewinding the fabric upon the board 25, the friction rollers 49, are rotated in a reverse direction to that in which they were rotated in unwinding the first half of the bolt, and the nut 51, and pointer 52, are thereupon returned to their normal position at "O" on the scale. When the fabric has been completely rewound upon the board 25, the operator detaches the board 40 and rod 27, from the heads 19, and removes the rod, leaving the board in the bolt.

More or less variation of the exact details of construction is possible without departing from the spirit of this invention, and I desire, therefore, not to limit myself to the exact form of construction shown and described, but intend in the following claims to point out all of the invention disclosed herein.

50 I claim as new, and desire to secure by Letters Patent:

1. In a machine for doubling and rewinding bolts of woven fabrics, a support for the full bolt, a winding drum upon which part 55 of the fabric is wound, a rewinding head, upon which the fabric is doubled and rewound, and mechanism for alternatively rotating said winding drum and rewinding head.

60 2. In a machine for doubling and rewinding woven fabric, a support for the full bolt, a winding drum, upon which approximately one-half of the fabric is wound, a rewinding device, upon which the fabric is doubled and rewound, a driving gear wheel, pinions,

one connected to said winding drum and one to said rewinding device, and means for bringing said driving gear wheel into mesh with either of said pinions.

3. In a machine for doubling and rewinding woven fabric, a rewinding device, comprising two rotatory heads, a board removably supported directly thereby, a rod secured to said heads, alongside of said board and removable therefrom independently of the board, over which rod the fabric is doubled, and means for rotating said heads, board and rod.

4. In a machine for doubling and rewinding fabric, two oppositely disposed rewinding heads, the one being spring pressed toward the other, each having an elongated socket member for the reception of the end of a board, and each head also having a socket for the reception of a rod, between which rod and board the middle of the fabric is placed, and driving means for rotating said heads.

5. In a machine for doubling and rewinding fabric, end frame members, two oppositely disposed rewinding heads, each formed with a central hub and an elongated socket member, shafts carried by said end frame members, and secured in said hubs, a spring for pressing one of said heads toward the other driving mechanism for the other shaft, and means for securing the middle portion of the fabric to said heads, including a board held in said socket members.

6. In a machine for doubling and rewinding fabric, two end-frame members, two oppositely disposed shafts carried by said end frame members, two rewinding heads, mounted upon said shafts, driving means for one of said shafts, and means for securing the middle of the fabric to said heads.

7. In a machine for doubling and rewinding fabric, two end-frame members, two oppositely disposed shafts carried by said end frame members, two rewinding heads, mounted upon said shafts, driving means for one of said shafts, and removable means for securing the middle of the fabric to said heads.

8. In a machine for doubling and rewinding fabric, two end-frame members, two oppositely disposed shafts carried by said end frame members, two rewinding heads, mounted upon said shafts, driving means for one of said shafts, a board adapted to be secured on said heads, and upon which the fabric is rewound, and means for holding the middle of the fabric on said board.

9. In a machine for doubling and rewinding fabric, end frame members, two oppositely disposed bolt carrying heads, a winding drum upon which part of the fabric is wound, two oppositely disposed rewinding heads, adapted to support a board upon which the fabric is doubled and rewound,

means for attaching the middle of the fabric to said board, and driving mechanism for said drum and rewinding heads.

10. In a machine for doubling and re-winding fabric, two oppositely disposed bolt carrying heads, each having a socket adjacent its ends, two rods adapted to extend through a full bolt of cloth, and removably held in said sockets, and plates, one slidably secured to each head and having portions over-lying the sockets, to retain the rods therein.

11. In a machine for doubling and re-winding fabric, a rotatory support for a full bolt of fabric, a rotatory support for holding a board upon which the doubled fabric is to be rewound, a drum upon which part of said fabric is to be wound temporarily, means for alternately driving said second support and said drum, and a measuring device having a friction roller resting on said fabric and rotated thereby when the fabric is moved past the roller, said measuring device indicating the length of fabric unwound from the full bolt, whereby when half of the fabric has been withdrawn from said full bolt, it may be doubled and rewound on the board carried by said second named support.

12. In a machine for doubling and re-winding fabric, a frame, a drum rotatively mounted in said frame, a pinion connected with said drum, rewinding heads rotatively mounted in said frame, connections between said heads, including a rod over which the fabric is doubled, a pinion connected with one of said heads, a gear carrying lever pivotally mounted upon said frame, and a driving gear wheel journaled upon said lever, said lever being capable of movement whereby said driving gear wheel is meshed with either pinion.

13. In a machine for doubling and re-winding fabric, a frame, a drum rotatively mounted in said frame, a pinion connected with said drum, rewinding heads rotatively mounted in said frame, connections between said heads, including a rod over which the fabric is doubled, a pinion connected with one of said heads, a gear carrying lever pivotally mounted upon said frame, a driving gear wheel journaled on said lever, and adapted to be moved into mesh with either of said pinions, and a bolt carried by said lever and co-operating with notches in said frame to hold said lever in either of said positions.

MORRIS J. HOFFMAN.
